UNITED STATES PATENT OFFICE.

GENNARO DE BELLIS, OF PHILADELPHIA, PENNSYLVANIA.

DESIGN FOR A REFLECTOR.

Application filed April 9, 1925. Serial No. 13,081. Term of patent 14 years.

To all whom it may concern:

Be it known that I, GENNARO DE BELLIS, a citizen of the United States, residing at Philadelphia, in the county of Philadelphia and State of Pennsylvania, have invented a new, original, and ornamental Design for Reflector, of which the following is a specification, reference being had to the accompanying drawing, forming a part shown thereof, in which—

Figure 1 is a side elevation of a reflector made in accordance with my new design,

Figure 2 is a vertical section through the reflector shown in Figure 1, and

Figure 3 an inverted plan view of the reflector shown in Figure 1.

I claim:

The ornamental design for a reflector, as shown.

GENNARO DE BELLIS.
